UNITED STATES PATENT OFFICE.

NICHOLAS S. VEDDER AND FRANCIS RITCHIE, OF TROY, AND TOBIAS S. HEISTER, OF LANSINGBURG, ASSIGNORS TO NICHOLAS S. VEDDER, OF TROY, NEW YORK.

DESIGN FOR A PARLOR-STOVE.

Specification forming part of Design No. 6,317, dated December 17, 1872.

To all whom it may concern:

Be it known that we, NICHOLAS S. VEDDER and FRANCIS RITCHIE, of the city of Troy, in the county of Rensselaer and State of New York, and TOBIAS S. HEISTER, of Lansingburg, in the said county and State, have jointly invented and produced a new and original Design for Parlor-Stoves, of which the following is a specification, reference being had to the accompanying wood cut or engraving of a stove which embodies our said design.

One part of our invention consists of the ornamental design for the removable cover A, as represented in the aforesaid cut. Another part consists of the design for the oval top B, as distinguished by the ornamented moldings c and d, shaped and arranged thereon as represented in the engraving. Another part consists of the ornaments e and f, as arranged at the top and bottom of the door-frame G so as to present the appearance represented in the said wood-cut. Another part consists of the design for the door H, as distinguished by the central ornament

i and border ornaments j, all shaped and arranged thereon so as to appear substantially as represented in the wood engraving. Another part consists of the design for the base-plate K, as distinguished by the ornamented moldings l and m thereon, as shown in the engraving, with or without the ornaments n n.

What we claim as our invention is—

1. The design for the cover A, as herein set forth.
2. The design for the oval top B, as described.
3. The ornaments e f arranged on the top and bottom portions of the door-frame G, and forming a part of the ornamental design thereof, as set forth.
4. The design for the door H, as described.
5. The design for the base K, as specified.
